(57) **CLAIM**

The ornamental design for a device for foot hygiene, as shown and described.

DESCRIPTION

FIG. 1 is a top-right perspective view of a device for foot hygiene;

FIG. 2 is a bottom-left perspective view thereof;

FIG. 3 is a top view thereof;

FIG. 4 is a bottom view thereof;

FIG. 5 is a front view thereof;

FIG. 6 is a rear view thereof;

FIG. 7 is a right side view thereof;

FIG. 8 is a left side view thereof;

FIG. 9 is a top-right perspective view of the device for foot hygiene in a closed configuration; and,

FIG. 10 is a top-right perspective view of the device for foot hygiene in a partially opened configuration.

The broken lines shown throughout the views depict portions of the device for foot hygiene which form no part of the claimed design.

1 Claim, 10 Drawing Sheets
